UNITED STATES PATENT OFFICE.

STANISLAV MICHNIEVITCH, OF LOS ANGELES, CALIFORNIA.

ORGAN.

Application filed June 21, 1926. Serial No. 117,589.

It is the object of this invention to provide an organ in which all nuances of artistic music may be obtained by means of fingering, through independent regulation of the expression and vibration of the different notes by varying the pressure of the fingers on the respective keys, and it is a further object of the invention to arrange the organ so that when a plurality of stops are employed, the pressure on the different keys of a single key-board will independently vary the expression and vibration of the corresponding notes in all of the stops which are drawn, in order that all shades of expression may be obtained, and the instrument thus adapted to solos, accompaniments or orchestras simply by fingering the one key-board and operating a register for each of the one or more auxiliary stops, without the necessity for a plurality of key-boards and a large number of draw-stops even with which it is impossible to obtain like results from the ordinary organ.

It is a still further object of the invention to provide registers for the auxiliary stops positioned so that they will be readily accessible from any point along the key-board without removing the fingers from the keys; and to arrange for increasingly resisting the finger pressure as the respective keys are depressed so that the sense of feeling will aid the player in obtaining the desired nuances of expression and vibration.

The invention is particularly adaptable to reed organs in which the notes are sounded by the vibration of tongues; and it is a further object of the invention to provide separate air channels and auxiliary resonators for the respective vibrators in order to provide clear and true tones from piano to forte, the auxiliary or qualifying resonators being of such material and shape as to be readily accommodated to their corresponding vibrators without necessitating their being of such excessive capacity as to make it impractical for their reception in a usual small parlor organ.

The vibrators are preferably operated by suction, with strikers starting the vibration; and it is a still further object of the invention to operate the strikers slightly in advance of the opening of the suction means, and to arrange the strikers so as to actuate all of the corresponding vibrators in the different stops, with relatively greater vibration imparted to the vibrators of the stops which are of standard pitch.

It is a still further object of the invention to provide the organ with a prolongment of novel construction whereby notes may be sustained at the same strength after the fingers have quit the corresponding keys.

Further objects of the invention will be readily understood from the following description of the accompanying drawings, in which:

Fig. 1 is a front elevation, partly broken away, showing the right half of the organ.

Fig. 2 is a front elevation of the left half of the organ with the front of the organ casing broken away.

Fig. 3 is a vertical section on the line 3—3 of Fig. 1.

Fig. 4 is a horizontal section on the line 4—4 of Fig. 1.

Fig. 5 is a similar view on the line 5—5 of Fig. 2.

Fig. 6 is a detail vertical section through the operating front rail of the organ and through the mechanism of one of the organ registers.

Fig. 7 is a detail side elevation of one of the wind box valves, showing the valve starting to open.

The main case of the organ may be of usual construction and includes the base 1, side walls 2 and front and back 3 and 4. A hinged cover 5 is provided for the top of the case and may be folded back to expose the key-board which is just above and in back of the front rail 6. The front of the case may be provided with openings 7 adapted for escape of sound and preferably covered with cloth or other suitable mesh material; and the front also has an opening 8 for the foot pedals 9 which are hinged to the base 1 and are adapted to operate the bellows which create the suction.

The sound producing mechanism is mounted in a frame received in the organ case; and this frame comprises a top 10, rear wall 11, and ends 13 which rest upon the base 1. The rear wall 11 is spaced an appreciable distance from the back of the organ case and a closed casing 12 which forms the wind box is mounted on the back of wall 11.

The bellows which are adapted to create the necessary suction for operating the organ, are mounted on the back 4 in rear of the casing 12, and are preferably four in number with the two middle bellows 15 connected to the respective foot pedals 9, and the two outer

bellows 16 forming reservoirs for the suction created by the middle bellows. The front boards of the bellows are supported at their upper ends by a transverse bar 17 having its ends connected to the sides 2 of the organ case; and the lower ends of the front boards which are inclined forwardly as shown in Fig. 3 are connected by a transverse conduit 18 which is also supported by the sides 2. The rear boards of the bellows are hinged at their upper ends as shown at 19, and their lower ends are adapted to swing rearwardly to expanded position.

The operating connections between pedals 9 and the middle bellows 15 are shown as links 20 pivoted at their respective ends to the swinging upper edges of the pedals and the swinging lower ends of the rear boards of the bellows. Springs 21 tend to shift the links so as to elevate the pedals and thereby compress the bellows; and depression of the pedals for expanding the bellows 15 creates a suction in the outer bellows 16, which are expanded by springs 22. As an instance of this arrangement the middle bellows 15 are provided with check valves 23 for discharging air to the atmosphere when bellows 15 are compressed; and check valves 24 open from conduit 18 to the middle bellows, and the outer bellows communicate with conduit 18 through ports 25, so that operating the foot pedals will draw air from the reservoir bellows 16 to create a vacuum therein. The reservoir bellows communicate with the casing 12 through nipples 26 in order to create a corresponding suction in the casing.

Casing 12 forms the wind box, the arrangement of which will depend upon the number of stops in the organ, and in the present instance the organ has four stops, two of which are of standard pitch, with the other two an octave higher and an octave lower respectively. One wind box controls the two stops which are of standard pitch, and a separate wind box is provided for each of the other two stops. The three wind boxes are accommodated in casing 12 by employing partitions 28 for dividing the casing into three super-imposed compartments which extend the entire width of the sound producing mechanism, and each of these compartments is in turn divided into upper and lower portions by means of partitions 29, the lower portion of each compartment being the wind box extending the width of the sound producing mechanism, and the upper portion of each compartment being divided by vertical partitions 30 into a plurality of separate and distinct valve chambers 31 alining with the respective sound producing mechanisms of an entire stop.

The nipples 26 open to the upper or main wind box 35 which controls the two stops of standard pitch, and wind boxes 36 and 37 for the stops an octave higher and an octave

lower, may be opened or shut off to the suction created in the main wind box in order that the auxiliary stops may be played or remain silent.

In each of the three compartments formed by partitions 28, the wind box is open to its respective valve chambers 31 through ports 38 in partitions 29. These ports taper to increased width at their rear ends, and the ports in each stop also gradually increase in width from the lowest to the highest note of the stop. The ports in the stop which is an octave higher are of slightly less width than the vertically alined ports for the stops of standard pitch, and the ports of the octave lower stop are of slightly greater width than said vertically alined ports of the standard stops.

Valves 39 in the respective chambers 31 control ports 38 and are normally seated by springs 40; and the valves rock to open position on pins 41 at their rear ends so that the narrow forward ends of ports 38 open first in order to provide gradually increasing valvular openings. Pliable strips 42 which may be of leather are provided at the seating surfaces of valves 39 to insure tight closing of the valves, and the strips are fixed to the respective ends of the valves but are loose along the lengths of the valves so that when a valve rocks to open position the suction from the wind box retards unseating of the pliable strip to provide an extremely gradual opening of the valve.

By opening the ports 38, suction in the wind boxes is communicated to the cooperating valve chambers, the suction in the respective valve chambers being independently controlled and regulated by varying the opening of the respective cooperating valves 39 in accordance with the touch upon the corresponding keys of the organ as hereinafter explained. The respective valve chambers open through the wall 11, with the openings for the valve chambers of the stops of standard pitch shown at 43 and the openings for the valve chambers of the higher and lower stops shown at 44 and 45.

A plate 48 for each of the four organ stops projects forwardly from the wall 11, and the vibrators or tongues 47 which produce the sound, together with a channel 50 and a resonator for each vibrator, are mounted upon the plates 48 with the vibrators of the different stops which are controlled by the same key in vertical alinement transversely of the organ. The plates 48 form conduits 49, with the conduits for the standard stops communicating at their inner ends with the respective openings 43, and the conduits for the higher and lower stops communicating with the openings 44 and 45 respectively.

The channels 50 are mounted on plates 48 and communicate with the conduits 49 so as to provide angles 51 in the air passageways 130

which are thus formed; and the channels are accommodated to their respective vibrators by gradually reducing their length and height from the lower notes to the higher notes of a stop. The resonators for the respective vibrators communicate with ports 53 in the channels 50; and the resonators are of proper graduated size and the ports 53 are positioned at points along the channels adapted to produce true and clear tones.

The resonators for the high notes of the organ are preferably pipes 54 of graduated length, and in practice are preferably of celluloid to provide the proper vibration; and in order to avoid increase in the size of the graduated pipes beyond the point where they can be conveniently received in the organ case, box resonators 55 of material such as wood, are preferably substituted for the pipes at the middle notes of the organ.

The series of graduated box resonators may be formed as integral casings divided by partitions 56 into individual resonators for the respective vibrators; and the series of resonators for the different stops may be nested in the organ case as shown in Figs. 2 and 3.

To avoid box resonators of impractical increasing size, they are preferably replaced at the low notes of the organ by graduated yieldable resonators 57, with the resonators of the octave lower stop upended where necessary to avoid the path of travel of pedals 9 as shown at 57^a. The yieldable resonators are preferably formed in pairs on wooden frames, 35 which include central wooden partitions 58, and are covered with resilient material such as rubber. The yieldable resonators preferably taper to reduced width at their ends which are opposite the ports 53, in order to provide space for expansion and contraction of their resilient sides, and the ports 53 of next adjacent channels 50 communicate with the individual resonators at the respective sides of central partitions 58.

45 The vibrators 47 are of standard construction comprising spring tongues mounted in slotted frames 59 which are received over the open forward ends of channels 50; and the succeeding vibrators of a stop are adapted to produce the successive notes of the musical scale with the vibrators of the respective stops an octave above and below the vibrators of the standard stops which are vertically aligned therewith.

55 Strikers impart initial vibration to tongues 47; and one set of strikers 61 control the vibrators of the two standard stops, while a second set of strikers 62 is provided for the vibrators of the two auxiliary stops. Each set of strikers is between the vibrators of the two stops which it controls; and the striker units are pivoted midway of their length and have heads 63 at their respective ends for engaging tongues of each of the two stops with which they cooperate.

The strikers 61 impart greater initial vibration than the strikers 62; and for this purpose the strikers 61 positively strike their tongues 47, while the strikers 62 are normally in engagement with their tongues so as to tension the same, and when operated simply release the tensioned tongues so that they may start to vibrate.

As an instance of this arrangement the strikers 61 are normally retracted by gravity, 75 and are swung against their tongues 47 by levers 64 when forked operating ends 65 of the levers are depressed. Shoulders 66 provide for release of strikers 61 by the levers 64 immediately after initial depression of the forks 65 so that the strikers are returned to normal retracted position. The strikers are then held against further movement by locking levers 67 which are moved into and retained in operative position until forks 65 are subsequently released.

The strikers 62 are normally held in engagement with their tongues by springs 68, and are swung against the tension of their springs to release the tongues by means of levers 69 which impinge against the striker units when their forked operating ends 70 are depressed.

The key-board of the organ is arranged so that depression of a key operates the corresponding vibrator in each of the four organ stops, the parts being so arranged that variation in pressure or touch upon the respective keys independently varies the degree of vibration of the corresponding vibrators. This result is obtained by varying the opening of valves 39 in accordance with the touch upon the corresponding keys, thereby varying the suction imparted to the corresponding vibrators and consequently varying their vibration. For this purpose the keys of the organ control vertical operating rods 72 which are guided through top 10 and engage the forked ends of the operating levers of corresponding strikers 61 and 62, and also control vertical 100 operating rods 73 which are slideable in casting 12 and cooperate with corresponding valves 39 for the different organ stops.

The key-board is mounted in a frame 75 which is pivoted at 76 above the top 10 and rests upon the base 77 of rail 6. The frame 75 includes a transverse rail 78 on which the key bars 79 are adapted to rock; and the front ends of the key bars form a usual key-board with the white and black keys 80 and 81 alternating in accordance with usual practice. The rear ends of the key bars may be counterweighted as shown at 82 and means are provided for exerting increasing yielding pressure against depression of the keys. As an instance of this arrangement the upper surfaces of the rear ends of the keybars are beveled as shown at 83 and spring fingers 84 are fixed to the key bars at said beveled ends, with stops 85 on the frame 75 spaced above the springs 130

and adapted for engagement thereby as the rear ends of the key bars are swung upwardly by depression of the keys.

- The under sides of the keys 80—81 engage 5 the upper ends of the corresponding operating rods 72 for depressing the latter and operating strikers 61—62 as the respective keys are depressed; and depression of the keys also elevates the corresponding operating rods 73 10 for operating the valves 39. For this purpose arms 87 below the respective key bars are adapted to rock on a bar 88 which is preferably supported on top 10; and the frontends of the arms are engaged by the respective operating rods 72 so that movement of the rods 15 will cause corresponding rocking of the arms, and the operating rods 73 are engaged by the rear ends of the rocker arms for movement thereby.
- 20 The operating rods 73 are arranged to open valves 39 slightly after operation of strikers 61—62 by the rods 72; and for this purpose the operating connections between rods 73 and valves 39 comprise levers 89 engaged by 25 the rods and hinged at their opposite ends to the valves as shown at 90. Stops 91 supported by the valves in spaced relation above the same are adapted for engagement of levers 89 when the latter are rocked, so as to provide a 30 lost motion connection opening the valves at a slight interval after the rods 73 are first shifted.

The operating connections for the valves as thus described, provides for varying the 35 opening of the corresponding valves 39 in accordance with the degree of movement of the respective rods 73, and movement of each rod being controlled by the rocking of the corresponding arm 87, which is in turn subjected to varying movement in accordance 40 with the degree of depression of the corresponding key of the organ, the opening of valves 39 is strictly in accordance with the touch or pressure upon the corresponding 45 keys.

The wind boxes 35, 36 and 37 are arranged whereby depression of the keys will play only the two standard stops of the organ, or will play one or both of the auxiliary stops in 50 combination with the standard stops. For this purpose the wind box 35 which controls the two standard stops, and which is always in communication with the reservoir bellows 16 through nipples 23, is adapted to be opened 55 or closed to one or both of the wind boxes 36—37 so that suction will be communicated thereto for playing the auxiliary stops.

As an instance of this arrangement casings 60 65 93 are mounted on the ends 13, with one of said casings overlying and communicating with wind boxes 35 and 36 through ports 94—95 in the end 13, and the other casing 93 overlying and communicating with wind boxes 35 and 37 through ports 94—96. Valves 97 slide in the respective casings 93

and normally close the ports 94 which communicate with wind box 35. The wind boxes 36—37 are thus shut off to the suction in wind box 35 and the auxiliary stops are consequently rendered inoperative. Movement of the 70 respective valves 97 to open position between ports 94—95 and 94—96, causes communication through casings 93 between wind boxes 35—36 and 35—37 in order to operate one or both of the auxiliary stops. 75

Valves 97 are operated by rods 98, and the latter are in turn actuated by bellows 99 which are normally expanded by springs 120 to shift the valves to normal position closing ports 94. The bellows are controlled by 80 registers 100—101 which are slide bars mounted on the front of rail 6 and extend the width of the key-board so that they are readily accessible when the fingers are on any keys. The operating connections between the 85 registers and the respective bellows include valves 102 normally spring closed and adapted to open to the atmosphere when engaged by tapering ends 103^a of the registers; and opening of valves 102 permits air to enter 90 valve casings 103 through conduits 104 in order to contract the bellows and depress rods 98 for opening valves 97. As an instance of this arrangement the valve casings 103 are divided by partitions 105 into compartments 95 103 and 107 communicating with bellows 99 and with conduits 108 which lead to the bellows 16. Partitions 105 have ports 109 opening therethrough, and compartments 106 are ported to the atmosphere as shown at 110. 100 Diaphragms 111 are mounted in compartments 107 with restricted conduits 112 normally equalizing the suction at the respective sides of the diaphragms; and the conduits 104 and 108 communicate with compartments 105 107 at opposite sides of the diaphragms. Valves 113 are movable between ports 109 and 110 to close one and open the other, and the valves are mounted on valve stems 115 which are operated by diaphragms 111. 110 When the diaphragms are in normal position, valves 113 close ports 109 so that the bellows are open to the atmosphere through ports 110 to permit expansion of the bellows by their springs, but when valves 102 are opened the diaphragms 111 are distorted by the unequal suction at their respective faces, and valve stems 115 are thereby shifted to open ports 109 and close ports 110 so that the bellows are contracted by the suction in 115 conduits 108.

The organ includes means whereby any note may be prolonged at the same strength after the fingers have quit its key, and for this purpose the arms 87 are adapted to be held in their rocked position after release of the corresponding keys so that the valves 39 controlled by the keys will remain open. As an instance of this arrangement fingers 121 are adapted to slide in under the rear ends of 125 130

arms 87 to retain the latter in elevated position, the fingers being pivoted to supporting rods 122 which are in turn pivoted in brackets 123 at the rear of frame 75. Rearward swinging of rods 122 to disengage the fingers from the rocker arms is limited by a transverse stop 123^a which is mounted in the sides 2 of the organ case; and the rods 122 are normally retracted against the stop by a hinged bar 124 which is drawn to operative position by a spring 125. The hinged bar may be swung forwardly to release rods 122 by a flexible connection 126 which is connected to a knee pedal 127 at the front of the organ. The knee pedal is positioned with relation to the right foot pedal 9 so that it may be engaged by the right knee, and for this purpose is shown connected to a support 130 by pivotal connection 131, with an arm 127^a of the pedal projecting beyond its pivotal mounting and extending into a recess 132 in the front rail 6 so that swinging the pedal by the knees will swing the arm 127^a transversely in recess 132. The flexible connection 126 is connected to the swinging end of arm 127^a and extends to the right through a bore 132 in front rail 6 as best shown in Fig. 6. The right-hand end of bore 132 opens rearwardly through the front rail 6 and a pulley 133 in the bore forms a guide for flexible connection 126 so that the latter may project rearwardly from the front rail and extend across the organ just beyond the right-hand end of the key board. The frame 75 is suitably apertured for passage of the flexible connection as shown at 135, and the rear end of the flexible connection is secured to the right-hand end of hinged bar 124 as shown at 134 in Fig 1. When the knee pedal is swung to a position abutting against a stop 128 so as to retract bar 124 by movement of the flexible connection 126, fingers 121 are free to slide in under the rear ends of any of the rocker arms which are elevated by depression of the corresponding keys. The fingers 121 will thus hold the rocker arms against return to normal position and thus retain the rods 73 in elevated position for prolonging the opening of valves 39 until knee pedal 127 is again released so that hinged bar 124 may return all of the rods 122 to inoperative position.

I claim:

1. An organ comprising sound producing means providing a plurality of stops, a key-board, a wind box, separate air channels communicating with the respective sound producing means, valves between the wind box and the respective air channels, means for independently controlling the valves of the sound producing means for the same note in the different stops by the respective keys, and means for independently varying the opening of the valves controlled by the respective

keys in accordance with the touch upon the corresponding keys. 65

2. An organ comprising a plurality of stops, a key-board having keys adapted to independently control the same note in the different stops, and registers for controlling certain entire stops extending the length of the key-board for equally convenient access thereto from any point along the key-board. 70

3. An organ including a key-board and having a plurality of stops, and a register for controlling a stop extending along the key-board equi-distantly spaced from a plurality of the keys. 75

4. An organ comprising sound producing means providing a plurality of stops, a key-board, a wind box, separate air channels communicating with the respective sound producing means, valves between the wind box and the respective air channels, means for independently controlling the valves of the sound producing means for the same note in the different stops by the respective keys, means for independently varying the opening of the valves controlled by the respective keys in accordance with the touch upon the corresponding keys, and registers for opening or closing all of the valves of certain stops to the wind-box. 80 85

5. An organ comprising sound producing means providing a plurality of stops, a key-board, a wind box, separate air channels communicating with the respective sound producing means, valves between the wind box and the respective air channels, means for independently controlling the valves of the sound producing means for the same note in the different stops by the respective keys, means for independently varying the opening of the valves controlled by the respective keys in accordance with the touch upon the corresponding keys, and registers for opening or closing all of the valves of certain stops to the wind box, said registers extending along the key-board adjacent the keys for convenient access thereto by the fingers at any point on the key-board. 90 95 100 105 110

6. An organ comprising sound producing means, a key-board, a wind box, separate air channels communicating with the respective sound producing means, valves between the wind box and the respective air channels, means for controlling the valves by the respective keys, means for independently varying the opening of the valves in accordance with the touch upon the corresponding keys, and means for exerting increasing yielding pressure against depression of the respective keys by the fingers. 115 120

7. A reed organ comprising vibrator tongues, separate air channels communicating with the respective tongues, a wind box, and valvular controls between the wind box and the respective air channels separated the 125

length of said channels from the vibrator tongues.

8. A reed organ comprising vibrator tongues, separate air channels communicating with the respective tongues and graduated in size to accommodate themselves to the respective tongues so as to produce true tones, a wind box, and valvular controls between the wind box and the respective air channels separated the length of said channels from the vibrator tongues.

9. A reed organ comprising vibrator tongues, separate resonators communicating with the respective tongues, a wind box, and valvular controls between the wind box and the respective vibrators.

10. An organ comprising sound producing vibrators, separate resonators communicating with the respective vibrators and graduated in size to accommodate themselves to the respective vibrators so as to produce true tones, the resonators for the vibrators which produce the low notes being of relatively yieldable material to eliminate the necessity for resonators of excessive size, a wind box, and valvular controls between the wind box and the respective vibrators.

11. An organ comprising sound producing vibrators, separate resonators communicating with the respective vibrators and graduated in size to accommodate themselves to the respective vibrators so as to produce true tones, the resonators for the vibrators which produce the high notes being of but slightly yieldable material and the resonators for the vibrators which produce the low notes being of relatively yieldable material so that the resonators may be of a size for practical accommodation in the organ.

40 12. An organ comprising sound producing vibrators, a key-board, strikers for the respective vibrators, a wind box, valvular controls between the wind box and the respective vibrators, means for actuating the strikers and the valvular controls by the respective keys, and means for causing operation of the strikers slightly in advance of the opening of the corresponding valvular controls.

13. An organ comprising sound producing vibrators providing a plurality of organ stops, a key-board, strikers for the respective vibrators, means for independently actuating the strikers for the vibrators which produce the same note in the different stops by the respective keys, said strikers being arranged to impart greater vibration to the vibrators which produce notes of standard pitch than to the corresponding vibrators for the auxiliary organ stops, valvular controls for the respective vibrators, and means for actuating the valvular controls by the respective keys.

14. An organ comprising sound producing means, a key-board, a wind box, valves between the wind box and the respective sound producing means controlled by the respective

keys, means for opening the valves in accordance with the touch upon the corresponding keys, and means for retaining the valves in the same open position to which they have been moved after the fingers have quit the keys.

15. An organ comprising sound producing means providing a plurality of stops, a key-board, a wind box, valves between the wind box and the respective sound producing means, means for controlling the valves by corresponding keys of the key-board, means for independently varying the opening of said corresponding valves in accordance with the touch upon their respective keys, and registers for opening or closing all of the valves of certain stops to the wind box.

16. An organ comprising sound producing means providing a plurality of stops, a key-board, a wind box, valves between the wind box and the respective sound producing means, means for controlling the valves by corresponding keys of the key-board, means for independently varying the opening of said corresponding valves in accordance with the touch upon their respective keys, and registers for opening or closing all of the valves of certain stops to the wind box, said registers extending along the key-board equi-distantly spaced from a plurality of the keys.

17. A reed organ comprising vibrator tongues, separate angular air channels of appreciable length communicating with the respective tongues, a wind box, and valvular controls between the wind box and the respective air channels.

18. A reed organ comprising vibrator tongues, a key-board, separate air channels communicating with the respective tongues, a wind box, valves between the wind box and the respective air channels, means for controlling the respective valves by the respective keys, and means for independently varying the opening of the respective valves in accordance with the touch upon the corresponding keys.

19. An organ comprising sound producing vibrators, and separate resonators communicating with the respective vibrators and graduated in size to accommodate themselves to the respective vibrators so as to produce true tones, the resonators for the vibrators which produce the high notes being of but slightly yieldable material so that said vibrators may be of a size for practical accommodation in the organ.

20. An organ comprising sound producing vibrators, a key-board, strikers for the respective vibrators, a wind box, valvular controls between the wind box and the respective vibrators, means for actuating the respective strikers and opening the respective valvular controls by corresponding respective keys, and means for varying the blow of the respective strikers and the opening of the re-

spective valvular controls in accordance with the pressure upon the corresponding keys.

21. An organ comprising sound producing vibrators providing a plurality of organ stops, and strikers for the respective vibrators adapted to impart greater vibration to the vibrators which produce notes of standard pitch than to the corresponding vibrators for the auxiliary organ stops.

10 22. In an organ, a sound producing means, a key, a wind box, a valve adapted to open the wind box to the sound producing means, a rod adapted to variably open the valve in accordance with the degree of movement of the rod, and an operating connection for moving the rod in accordance with the degree of depression of the key.

20 23. In an organ comprising a plurality of stops, sound producing means for the same note in different stops, a key, wind boxes for the different stops, valves between the respective wind boxes and the sound producing means for the same note in the different stops, a rod adapted to variably open said valves of 25 the sound producing means for the same note in the different stops in accordance with the degree of movement of the rod, and an operating connection for moving the rod in accordance with the degree of depression of 30 the key.

24. In an organ comprising a plurality of stops, a key-board, and a register for controlling a stop comprising an elongated bar extending the length of the key-board in 35 front of the latter and adapted for operative movement by manual engagement of any portion of the bar.

25. In an organ comprising a plurality of stops, sound producing means for the same note in different stops, a key, a main wind box, secondary wind boxes for the respective stops, registers for opening or closing certain of the secondary wind boxes to the main wind box, valves between the respective secondary 45 wind boxes and the sound producing means for the same note in the different stops, a rod adapted to variably open said valves of the sound producing means for the same note in the different stops in accordance with the degree 50 of movement of the rod, and an operating connection for moving the rod in accordance with the degree of depression of the key.

26. An organ comprising sound producing means, a key-board, a wind box, valves between the wind box and the respective sound producing means, means for controlling the respective valves by the respective keys, means for independently varying the opening of the respective valves in accordance 55 with the touch upon the corresponding keys, and a spring engaging the keys so as to exert increasing yielding pressure against depression thereof.

27. In an organ, a vibrator tongue, a 60 striker for said tongue, a key, a wind box, a

valve adapted to open the wind box to the vibrator tongue, a rod adapted to open the valve, a lost motion connection between the rod and valve, a rod adapted to actuate the striker, and an operating connection between the key and said rods.

28. A reed organ comprising vibrator tongues, separate air channels communicating with the respective tongues, a wind box, valvular controls between the wind box and the respective air channels separated the length of said channels from the vibrator tongues, and separate resonators communicating with the respective air channels adjacent the corresponding vibrator tongues.

29. An organ comprising sound producing vibrators, a keyboard, strikers for the respective vibrators, a wind box, valvular controls between the wind box and the respective vibrators, means for actuating the strikers and the valvular controls by the respective keys, means for causing operation of the strikers slightly in advance of the opening of the corresponding valvular controls, and means for varying opening of the respective valvular controls in accordance with the pressure upon the corresponding keys.

30. A reed organ comprising vibrator tongues, a key-board, separate air channels communicating with the respective tongues and graduated in size to accommodate themselves to the respective tongues so as to produce true tones, a wind box, valves between the wind box and the respective air channels, means for independently varying the opening of the respective valves in accordance with the touch upon the corresponding keys.

31. A reed organ comprising vibrator tongues, a key-board, separate air channels communicating with the respective tongues, a wind box, valves between the wind box and the respective air channels, separate resonators communicating with the respective air channels adjacent the corresponding tongues, means for controlling the respective valves by the respective keys, and means for independently varying the opening of the respective valves in accordance with the touch upon the corresponding keys.

32. A reed organ comprising vibrator tongues, a key-board, separate angular air channels of appreciable length communicating with the respective tongues, a wind box, valves between the wind box and the respective air channels, means for controlling the respective valves by the respective keys, and means for independently varying the opening of the respective valves in accordance with the touch upon the corresponding keys.

33. A reed organ comprising valvular tongues, separate resonators communicating with the respective tongues, a key-board, a wind box, valves between the wind box and the respective tongues, means for controlling the respective valves by the respective keys,

and means for independently varying the opening of the respective valves in accordance with the touch upon the corresponding keys.

- 5 34. An organ comprising sound producing vibrators, a key-board, strikers for the respective vibrators, a wind box, valvular controls between the wind box and the respective vibrators, means for actuating the respective 10 strikers and opening the respective valvular controls by corresponding respective keys, and means for varying opening of the respective valvular controls in accordance with the pressure upon the corresponding keys.
- 15 35. An organ comprising sound producing vibrators providing a plurality of organ stops, strikers for the respective vibrators adapted to impart greater vibration to the vibrators which produce notes of standard 20 pitch than to the corresponding vibrators for the auxiliary organ stops, a wind box, valvular controls between the wind box and the respective vibrators, means for actuating the respective strikers and opening the respective 25 valvular controls by corresponding respective keys, and means for varying opening of the respective valvular controls in ac-

cordance with the pressure upon the corresponding keys.

36. In an organ, a sound producing means, 30 a key, a wind box, an air channel communicating with the sound producing means, a valve adapted to open the wind box to the air channel, a rod adapted to variably open the valve in accordance with the degree of movement of 35 the rod, and an operating connection for moving the rod in accordance with the degree of depression of the key.

37. A organ comprising sound producing means, a key-board, separate air channels 40 communicating with the respective sound producing means, a wind box, valves between the wind box and the respective air channels, means for controlling the respective valves by the respective keys, means for independently 45 varying the opening of the respective valves in accordance with the touch upon the corresponding keys, and a spring engaging the keys so as to exert increasing yielding pressure against depression thereof.

50 In testimony whereof he has affixed his signature to this specification.

STANISLAV MICHNIEVITCH.
